HOOK

Erick Erickson, Astoria, Oreg.

Application August 10, 1937, Serial No. 158,438

2 Claims. (Cl. 24—241)

This invention relates to hooks, and the present invention is concerned with a hook of the type disclosed in Patent No. 1,237,885, granted to me under date of August 21, 1917.

5 The present invention involves certain new and useful improvements over the type of hook aforesaid, and has particular reference to improved means for securing the hook closed and from becoming accidentally detached from the work with which it may be engaged.

The invention together with its objects and advantages will be best understood from a study of the following description taken in connection with the accompanying drawing, wherein:

15 Figure 1 is a side view of the hook with certain parts broken away and shown in section.

Figure 2 is a top plan view of the hook.

Figure 3 is a sectional view taken substantially on the line 3—3 of Figure 2, and

20 Figure 4 is a fragmentary view of the sheath and sleeve constituting the free end construction of a keeper unit.

Referring to the drawing by reference numerals it will be seen that in the preferred embodiment 25 thereof the hook comprises a body 1 having an integral bill 2. A clevis 3 is connected with the body 1 through the medium of a bolt and nut 4.

Further there is provided a keeper unit 5 which at one end is notched or recessed as at 6 to receive the end of the body 1 remote from the bill 2, and the keeper unit 5 is pivoted to the body 1 through the medium of the aforementioned bolt and nut 4.

At its free end the keeper unit 5 is enlarged at 35 5' to form a sleeve retention head provided with a longitudinal slot 7 of a width to receive the bill 2 of the hook, and said bill is provided with a transverse rib or shoulder 8, with which the web portion 8' is adapted to engage as clearly shown in Figures 1 and 2.

At said slotted end the keeper 5 is provided with a peripheral groove 11 which accommodates a locking or retaining sleeve 12.

Sleeve 12 is of a length slightly less than the 45 length of the groove 11 and is rotatable about the keeper 5 as an axis.

Sleeve 12 is provided with a notch 13 that is adapted to aline with the underside of the slot 7 in the keeper 5 so as to permit free passage of 50 the bill 2 into and out of the slot 7.

With the bill 2 arranged in the slot 7 the same is retained in said slot against casual displacement by rotating the sleeve 12 for positioning the notch 13 in the sleeve out of alinement with 55 the bottom side of the slot 7 or to the position shown in the drawing.

It is believed to be clearly apparent that with the sleeve in the mentioned position a separation of the bill 2 and keeper 5 is positively precluded.

To disengage the hook and keeper, it is only necessary to rotate the sleeve 12 to aline the notch 13 therein with the bottom of the slot 7. This leaves the bill 2 free to pass out of the slot through the bottom side of the latter.

In conclusion and briefly stated, the hook embodying my invention comprises a body and a 10 beit. A keeper is pivoted to the body of a hook at one end of the hook remote from the bill, and is provided at its free end with a sheath for receiving the bill of the hook. Mounted on the keeper, and rotatable about the axis of the keeper 15 is a sleeve adapted to retain the bill in the sheath. The sleeve is provided with a notch which is adapted to align with the open side of the sheath to permit movement of the bill into and out of the sheath.

It will thus be seen that I have provided a hook which is so equipped as to positively retain the hook engaged with the work such as the link of a chain, or the like, and that the means for retaining the hook so positively engaged with the work has numerous advantages over the hook shown in my aforementioned patent, as will be clearly appreciated by those skilled in the art.

Having thus described the invention what is claimed as new is:—

1. A hook comprising a body and a bill, a keeper pivoted to the body of the hook at the end of the hook body remote from the bill, and said keeper at the free end thereof being provided with a sheath for receiving the bill, and a sleeve on said end of the keeper and rotatable about the keeper as an axis, said sleeve being engageable with the bill for retaining the latter within said sheath, and said sleeve being also provided with a notch adapted to aline with the open side of said sheath to permit movement of the bill into and out of said sheath.

2. A hook comprising a body and a bill, a keeper pivoted to the body of a hook at the end of the body remote from the bill, and said keeper at the free end thereof being provided with a sheath for receiving the bill, said keeper being reduced in cross sectional dimensions to form a groove, and a sleeve rotatable in said groove, said sleeve being engageable with the bill for retaining the latter within said sheath, said sleeve being also provided with a notch adapted to align with the open side of said sheath to permit movement of the bill into and out of said sheath.
